C. E. BROOKS

LEDGER STAND

Filed March 24, 1924

UNITED STATES PATENT OFFICE.

CLYDE EVERETT BROOKS, OF MASON CITY, IOWA.

LEDGER STAND.

Application filed March 24, 1924. Serial No. 701,485.

To all whom it may concern:

Be it known that I, CLYDE EVERETT BROOKS, a citizen of the United States, and a resident of Mason City, county of Cerro 5 Gordo, State of Iowa, have invented a new and useful Improvement in Ledger Stands, of which the following is a full, clear, and exact description.

My invention relates to improvements in 10 ledger stands, and more particularly to that type of stand which is adjustable as to height, and it consists in the combinations, constructions, and arrangements herein described and claimed.

15 An object of my invention is to provide a ledger stand of the type described by the use of which the necessity of lifting ledgers from one support to another is entirely obviated. Certain ledgers employed in offices 20 weigh in the neighborhood of fifty-five pounds, and are too heavy and cumbersome to be lifted about freely, as in moving the ledger from one side of a posting machine to the opposite side, and at a different height 25 from the floor.

A further object of my invention is to provide a device of the type described which will remain in its adjusted position and in which the platform for supporting the ledger 30 may be elevated or lowered with ease.

A further object of my invention is to provide a device of the type described in which means for adjustment as to weight of the ledger supported thereupon is provided.

35 A further object of my invention is to provide a ledger stand of the type described in which means is provided for maintaining the platform in a stable condition at all 40 times.

Other objects and advantages will appear in the following specification, and the novel features of the invention will be particularly pointed out in the appended claims.

45 My invention is illustrated in the accompanying drawings forming part of this application, in which—

Figure 1 is a front elevation of an embodiment of my invention, and

50 Figure 2 is a side elevation of the mechanism illustrated in Figure 1.

In carrying out my invention I make use of a base member 1 supported upon suitable casters 2. A collapsible frame consisting of a pair of U-shaped members 3 and 4, 55 pivotally supported upon the base 1 at 5,

(see Figure 2) has pivotally connected thereto complementary frames 6 and 7 respectively upon which the ledger platform 8 is supported. The pivotal connection of the frames 3 and 6 and 4 and 7 is indicated at 9, (see Figure 1). The connection between the platform 8 and the upper ends 10 of the frames 6 and 7 consists in a U-shaped hanger secured to the undersurface of the platform 8, and pivotally connected at 12 with the adjacent ends 10 of the frames 6 and 7.

In order that the platform 8 may be stable at all times and not tilt upon its relatively narrow support 12—12, a pair of collapsible 70 guide members 13 is provided and connected on each side of the frames 3—6 and 3—7, (see Fig. 1). These collapsible guide members consist of a pair of frames 14 pivotally connected to one another by a hinge 15 75 pivotally connected at their ends by hinges 16 to blocks 17 secured to the under side of the platform 8 and to the upper side of the base 1 respectively. The hinges 16 and 15 are sufficiently wide to prevent any tilting 80 of the platform 8, yet to not interfere in any way with the vertical elevation or lowering of the platform.

Resilient means for normally elevating the platform 8 is provided in tension springs 85 18 secured at their uppermost ends to rods 19 carried by the lowermost portions of the frames 6 and 7 respectively. The opposite ends of the tension springs 18 are connected to blocks 20 at the opposite sides of the base 90 1 to which the frames 6 or 7, connected with the upper ends of the springs 18, are associated. These blocks 20 are provided with a threaded bore therethrough, through which a shaft 21 having right hand threads for the 95 remaining block is disposed. The shaft 21 is provided with a crank handle 24 by means of which the shaft may be rotated to vary the tension of the springs 18.

From the foregoing description of the 100 various parts of the device, the operation thereof may be readily understood. Let us assume that a ledger is placed upon the platform 8 and that it is desired to post this ledger. In posting the ledger it is preferable 105 to place the ledger on the right hand side of the posting machine and about 30 inches from the floor. After the item has been posted, the entire stand is moved upon its casters 2 to the left hand side of the posting machine for proving. In proving the 110 ledger it is usually necessary to have the

ledger higher from the floor; approximately 39 inches instead of 30. Heretofore it has been necessary to lift the heavy ledger to a higher supporting surface. With my improved support, however, it is merely necessary to lift up on the platform 8. The springs 18 will assist in this movement and prevent collapse of the frames 3-6 and 4-7.

10 If the ledger is a particularly heavy one, the tension of the springs 18 will be increased, while if it is a light one, it may be decreased. This increase and decrease in the tension of the springs 18 is brought about 15 by rotation of the shaft 21 by means of its crank 24.

I claim:

1. A ledger stand of the character described comprising a base member, a ledger supporting platform, a collapsible means comprising a pair of frames pivotally connected with one another and with said base member and said ledger supporting platform respectively, spring means associated 25 with said collapsible means for yieldingly

elevating said platform, and a pair of frames pivotally mounted to each other and to said platform and said base respectively, and having their axes disposed transverse to the axes of said collapsible means, whereby said base member and said platform are maintained substantially parallel at all times. 30

2. A ledger stand of the character described comprising a base member, a ledger supporting platform, a collapsible means comprising a pair of frames pivotally connected with one another and with said base member and said ledger supporting platform respectively, adjustable spring means associated 35 with said collapsible means for yieldingly elevating said platform, and a pair of frames pivotally mounted to each other and to said platform and said base respectively, and having their axes disposed transverse to the axes of said collapsible means, whereby 40 said base member and said platform are maintained substantially parallel at all times. 45

CLYDE EVERETT BROOKS.
